ELECTRICAL PROTECTIVE SYSTEM

Floyd D. Johnson, Forest Hills, Pa., assignor to
 Westinghouse Electric & Manufacturing Company, East Pittsburgh, Pa., a corporation of Pennsylvania

Application April 11, 1941, Serial No. 388,080

9 Claims. (Cl. 175—294)

This invention relates to electrical control systems, and it has particular relation to directional relays for protecting electrical circuits and apparatus.

Conventional prior art directional relays generally employ rotatively mounted armatures for operating control contacts. For example, induction type directional relays are extensively employed. Although such relays have excellent characteristics, the art has numerous applications wherein a simple, sturdy and inexpensive directional relay is desired.

In accordance with the invention a directional control device or relay is provided which employs a pair of simple translating or operating means. This means may take the form of a thermally responsive device such as a bimetallic thermostat, metallic bellows, or thermocouple. As a further example, the means may take the form of a magnetic device operating by magnetic attraction or repulsion.

Two translating or operating means are disposed with their outputs in opposition to each other. Circuit controlling means such as electrical contacts are associated with the translating or operating means to be actuated differentially thereby.

One of the operating means is designed for energization normally in accordance with the sum of two quantities. For example, if the relay is designed to respond to the direction of energy flow in an electrical circuit, the translating or operating means is energized in accordance with the sum of the voltage and current present in the circuit. When the energy flow in the circuit reverses, the translating or operating means then is energized in accordance with the difference between the voltage and current present in the circuit. Consequently, the translating or operating means may be designed to discriminate between the two directions of energy flow.

When one of the translating or operating means is normally energized in accordance with the sum of two quantities, the remaining means preferably is energized in accordance with the difference between the same quantities. With such normal energizations of the two means, when energy flow reverses in the associated electrical circuit in the case of a directional relay, the sum and difference energizations for the two means are interchanged. This greatly increases the sensitivity and effectiveness of the relay.

It is, therefore, an object of the invention to provide an electrical directional device having a simple and sturdy design.

It is a further object of the invention to provide a directional element which normally is energized in accordance with the sum of two quantities and which under abnormal conditions is energized in accordance with the difference between the same quantities.

It is a further object of the invention to provide a control device differentially responsive to the output of opposed operating means, which means are normally energized, respectively, in accordance with the sum and difference of two quantities.

It is a still further object of the invention to provide a directional relay system having two opposed thermally responsive elements normally energized, respectively, in accordance with the sum and the difference of two quantities.

It is a still further object of the invention to provide a directional relay system having two opposed magnetic responsive elements normally energized, respectively, in accordance with the sum and the difference of two quantities.

Other objects of the invention will be apparent from the following description taken in conjunction with the accompanying drawings, in which:

Figure 1 is a schematic view of an electrical system embodying the invention; and

Figs. 2 to 9 are schematic views showing modifications of the system disclosed in Fig. 1.

Referring to the drawings, Figure 1 shows an alternating current electrical system including a circuit 1 for supplying electrical energy from a suitable source such as a transformer 2 to a load. Although the system may vary appreciably and may be a polyphase system, for the purpose of illustration, the circuit 1 is a single phase circuit having the midpoint of the secondary winding of the transformer 2 grounded. For the purpose of controlling the connection of the load to the transformer 2 a circuit breaker 3 is provided. This circuit breaker includes a tripping latch 3a and a conventional tripping solenoid 4 having an energizing battery 5 associated therewith.

In order to control the tripping of the circuit breaker 3 in accordance with the direction of energy flow in the circuit 1, a directional relay 6 is provided. This directional relay includes circuit controlling means such as a movable contact 7 and a fixed contact 8. Movement of the movable contact 7 is effected by a pair of translating or operating means 9 and 10, which in Fig. 1 are represented as bimetallic thermostats. Each of these bimetallic thermostats has one end fixed to a stationary common support 11. A

bridge 12 connects the free ends of the thermostats and carries the movable contact 7.

The bimetallic thermostats 9 and 10 are designed to move in opposition to each other as they are heated. This movement may be either away from or towards each other, but in the specific example of Fig. 1 the movements of the thermostats 9 and 10 when heated are assumed to be in the direction of the arrows *a* and *b*, respectively. Since a variation in temperature tends to urge the thermostats in opposite directions, ambient temperature variations have substantially no effect on the movable contact 7. In order to permit movement of the bimetallic thermostats without undue distortion thereof the bridge 12 may be connected to each of the bimetallic thermostats through a pivot connection. In the embodiment of Fig. 1 the bridge 12 may be provided with pointed or knife-blade ends for facilitating flexure of the bimetallic thermostats.

The bimetallic thermostats 9 and 10 may be heated in various ways. If desired, separate heaters 13 and 14 may be provided for the respective bimetallic thermostats.

As previously explained, it is desired that the heaters be energized respectively in accordance with the sum of, and difference between, the same quantities under normal operating conditions of the circuit 1. Such energization may be provided by several constructions. In the embodiment of Fig. 1 the heaters 13 and 14 are connected with the secondary winding of a current transformer 15 in a series circuit. If the current transformer 15 is associated with one of the conductors of the circuit 1, a current component I_i traverses both of the heaters 13 and 14, which is substantially proportional to the current I flowing in the circuit 1. For the purpose of illustration, the current component I_i at a predetermined point in the wave of voltage applied to the circuit 1 is assumed to flow upwardly in the heater 13 and downwardly in the heater 14. Since the system of Fig. 1 is an alternating current system the various current and voltage quantities may be treated as vector quantities.

Each of the heaters 13 and 14 also is energized by an additional current component I_e which is proportional to the voltage E of circuit 1. In the specific embodiment of Fig. 1 such additional energization is provided by connecting a conductor of the circuit 1 to a tap 15a centrally disposed on the secondary winding of the current transformer 15. By inspection of Fig. 1, it will be noted that with respect to the voltage to ground E of the circuit 1 the two heaters 13 and 14 are connected in parallel to a common resistor 16. This current component I_e at the selected point of the voltage wave is assumed to flow downward in each of the heaters 13 and 14.

Since the current $2I_e$ flows through the centrally disposed tap on the secondary winding of the current transformer 15, the current divides equally and flows in opposite directions through the two halves of the secondary winding. For this reason the current transformer offers substantially no inductive reactance to the current I_e . In view of the fact that the heaters 13 and 14 and the resistor 16 offer substantially pure resistance to the flow of the current I_e , it follows that the current I_e is substantially in phase with the voltage E .

From the foregoing discussion it will be appreciated that for normal unity power factor conditions in the circuit 1, the component currents

I_e and I_i add in the heater 14 and subtract in the heater 13. Consequently, the resultant force exerted by the two bimetallic thermostats 9 and 10 operates to move the movable contact 7 away from the contact 8.

If the direction of energy flow in the circuit 1 reverses and the power factor remains at unity, the component currents I_e and I_i add in the heater 13 and subtract in the heater 14. Therefore, the resultant force operates to move the movable contact 7 into engagement with the fixed contact 8 to trip the circuit breaker 3.

The performance of the system illustrated in Fig. 1 may be understood more clearly from a brief mathematical analysis thereof. In the following analysis the line-to-ground voltage E is employed as a reference for phase angle relationships. Since an alternating current system is involved, the following relationships hold.

Values for the component currents I_e and I_i may be indicated as follows:

$$I_e = \frac{E}{2R} (\cos \theta + j \sin \theta) = cE \quad (1)$$

$$I_i = kI (\cos \theta + j \sin \theta) \quad (2)$$

where c and k denote constants, θ represents the phase angle between voltage and current (θ is assumed to be positive for currents which lead the reference voltage), and R represents the equivalent resistance of the circuit carrying the current I_e .

The sum of the component currents in one heater is depicted by the following expression wherein the quantities in parenthesis represent real and reactive current components, respectively:

$$I_e + I_i = (cE + kI \cos \theta) + j(kI \sin \theta) \quad (3)$$

The difference of the component currents in the remaining heater is:

$$I_e - I_i = (cE - kI \cos \theta) - j(kI \sin \theta) \quad (4)$$

Since the temperature developed by a heater having a resistance w is proportional substantially to the square of the scalar value of the resultant current flowing therethrough, the forces exerted by the thermostats may be correspondingly represented. Recalling that the square of the scalar value of the resultant current flowing through each heater is equal to the sum of the squares of the real and reactive components thereof, the temperatures developed by the respective heaters are represented by:

$$w(I_e + I_i)^2 = w[(cE + kI \cos \theta)^2 + (kI \sin \theta)^2] \quad (5)$$

$$w(I_e - I_i)^2 = w[(cE - kI \cos \theta)^2 + (kI \sin \theta)^2] \quad (6)$$

As previously pointed out, the thermostats oppose each other. Consequently, the resultant force operating on the thermostat assembly may be represented by the difference between Equations 5 and 6, or the resultant force

$$F = w(I_e + I_i)^2 - w(I_e - I_i)^2 \quad (7)$$

$$\alpha 4wck(EI \cos \theta) \quad (8)$$

From Equation 8 it is clear that the resultant force operating on the contacts is proportional to the power flowing in the electrical circuit as represented by the well-known expression " $EI \cos \theta$."

For angles between 270° and 90° , $\cos \theta$ is positive. Values of $\cos \theta$ for angles between 90° and 270° are negative. Consequently the resultant force F varies in sign in accordance with the di-

rection of energy flow in the electrical circuit, and the direction of movement of the contact also is dependent on the direction of energy flow.

Although only one directional relay 6 is disclosed in Fig. 1, as many additional relays may be employed as are required. For example, a pair of movable contacts 7a and 8a are shown connected in parallel with the contacts 7 and 8. Closure of the additional contacts 7a and 8a also operates to complete a tripping circuit for the tripping solenoid 4. These contacts 7a and 8a may be the movable and fixed contacts, respectively, of a directional relay similar to the relay 6 and associated with the remaining conductor of the circuit 1.

If desired, an auxiliary contact 17 may be associated with the relay 6 for completing a control circuit when energy flowing in the normal direction in the circuit 1 exceeds a predetermined value. In the specific example of Fig. 1, excessive energy flowing in a normal direction actuates the movable contact 7 into engagement with the fixed contact 17 to complete a tripping circuit for the tripping solenoid 4.

In Fig. 2 a directional device 6a is disclosed which corresponds to the directional relay 6 of Fig. 1. One of the bimetallic thermostats 9 of the device 6a is positioned to engage directly the tripping latch 3a of the circuit breaker 3. From an inspection of Fig. 2 it will be noted that no contacts are required.

Fig. 2 also discloses a modified method of heating the bimetallic elements 9 and 10 of the directional device 6a. These bimetallic elements are connected directly in a series circuit with the secondary of the transformer 15. The free ends of the bimetallic thermostats are bridged by a conductor 18 through which the bimetallic thermostats are connected to the resistor 16. Since the bimetallic thermostats inherently have electrical resistance, current flowing therethrough, operates to heat the thermostats directly, thereby dispensing with the heaters 13 and 14 provided in Fig. 1. Since the system disclosed in Fig. 2 otherwise conforms to that shown in Fig. 1, it is believed that the operation thereof is clear.

The embodiment 6b illustrated in Fig. 3 is similar to that of Fig. 1 except for the replacement of the bimetallic thermostats 9 and 10 by flexible metallic bellows 9a and 10a. One end of each of the bellows is attached to a fixed support 11a. The remaining ends of the bellows are connected to a common movable contact 7a which operates to bridge fixed contacts 8a or 17a. Bridging of the contacts 8a results in the completion of a tripping circuit for the tripping solenoid 4.

Thermally responsive metallic bellows are well known in the art. Such bellows may contain a fluid having a temperature coefficient of expansion or a vapor pressure which varies appreciably with temperature. Consequently, when the bellows 10a is heated, the movable contact 7a is urged into engagement with the fixed contacts 17a. Similarly, when the bellows 9a is heated the movable contact 7a is urged into engagement with the fixed contacts 8a. Since the system of Fig. 3 otherwise corresponds to that of Fig. 1, it is believed that the operation thereof will be understood from the foregoing description.

As previously pointed out in discussing Fig. 2, it is possible to eliminate all contacts from the directional device. A further modification where- 70 contacts may be eliminated is depicted in Fig.

4. In Fig. 4 a directional device 6c is disclosed wherein the component parts are similar to those of Fig. 1 except for a substitution of thermocouples 9b and 10b for the bimetallic thermostats 9 and 10. As well understood in the art, a thermocouple has a direct current output which varies in accordance with the temperature to which the thermocouple is heated. In Fig. 4 the thermocouples 9b and 10b are heated, respectively, by the heaters 13 and 14. The outputs of the thermocouples 9b and 10b are connected in opposition for the purpose of controlling a tripping solenoid 4a which is polarized to respond to a predetermined polarity of the resultant thermocouple output. Consequently, the tripping solenoid 4a is energized in accordance with the difference between the outputs of the thermocouples 9b and 10b. If desired, an amplifier 19 may be inserted between the thermocouples and the tripping solenoid 4a for the purpose of amplifying the resultant output of the thermocouples.

In certain applications it may be undesirable to provide a centrally disposed tap for the secondary winding of the current transformer 15. In such applications the modifications illustrated in Fig. 5 may be employed. The only difference between the relay 6d disclosed in Fig. 5 and that shown in Fig. 1 resides in the path offered for the current component Ie. It will be noted that one terminal of the secondary winding of the current transformer 15 is connected through a conductor 20 to one conductor of the circuit 1. In addition, an auxiliary heater 21 is inserted between the resistor 16 and the heaters 13 and 14. This auxiliary heater is positioned to heat the bimetallic thermostat 9. Tracing the flow of the current components Ie and II, it will be noted that the component Ie flows through the heaters 13 and 14 in the same manner as in Fig. 1. However, the current component Ie now flows from the conductor 20 through the heater 14, the auxiliary heater 21 and the resistor 16 to ground. Since separate heaters 13 and 21, associated with the bimetallic thermostat 9, are provided for the current components, it follows that the resultant heating effect of the current components on the bimetallic thermostat 9 must be the same regardless of the direction of energy flow in the circuit 1. Therefore, the only discrimination between the directions of energy flow in the circuit 1 is that provided by the heater 14 wherein the current components Ie and II either add or subtract, depending upon the direction of energy flow. Although this energy responsive discrimination may be employed for controlling the circuit breaker 3, the relay 6d of Fig. 5 is not as sensitive as the relay 6 of Fig. 1.

In the previous discussion, it is pointed out that the methods for energizing the directional relay or device may vary appreciably. A further variation is disclosed in Fig. 6. In this figure the relay 6 of Fig. 1 is employed for controlling the circuit breaker 3. By inspection of the circuit connections, it will be noted that the heaters 13 and 14 of Fig. 6 are connected in series with the secondary winding of a voltage transformer 22. The primary of the voltage transformer 22 is connected across the circuit 1. One conductor of the circuit 1 is connected to a centrally disposed tap 22a on the secondary winding of the voltage transformer 22. Current flowing in this conductor divides between the two halves of the secondary winding and flows through the heaters 13 and 14 before reentering the circuit 1 through a conductor 23. In certain cases it may be de-

sirable to supply this current to the heaters through a current transformer (not shown) associated with the circuit 1 as well known in the art.

The direction of flow of the current components I_e and I_i is shown in Fig. 6 for a predetermined point on the voltage wave. It will be noted that the current component I_e flows downwardly in one of the heaters 14 and upwardly in the remaining heater 13, whereas the current component I_i flows downwardly in each of the heaters. Consequently, the current components add in one of the heaters 14 and subtract in the remaining heater 13. If the direction of energy flow in the circuit 1 reverses, the current components I_e and I_i add in the heater 13 and subtract in the heater 14. The analysis presented for Fig. 1 also applies for Fig. 6.

In the modifications thus far described the translating or operating means have taken the form of thermally responsive devices, such as bimetallic thermostats, metallic bellows, or thermocouples. It is also possible to employ magnetic devices for this purpose. Such a device is illustrated in Fig. 7.

Referring to Fig. 7, a directional relay 6e is disclosed which corresponds to the relay 6 of Fig. 1 except for the replacement of the bimetallic thermostats 9 and 10 by magnetic devices 9c and 10c and the replacement of heaters 13 and 14 by energizing windings 13a and 14a. From an inspection of Fig. 7 it will be observed that each of the magnetic devices 9c and 10c includes a projecting pole element 24 surrounded by one of the energizing windings and includes magnetic return paths 25. A common armature structure 26 is associated with the magnetic devices 9c and 10c and has a first armature portion 27 extending to a point adjacent the pole element 24 of the magnetic device 9c and a second armature portion 28 extending to a point adjacent the pole element 24 of the magnetic device 10c. The armature structure 26 is reciprocable relative to the magnetic devices 9c and 10c. The movable contact 7 is carried by the armature structure 26 on a pin 29 for movement into and out of engagement with the fixed contact 8.

Normally the armature structure 26 is biased by means of a spring 30 against a fixed stop 31. The purpose of the stop 31 is to position the armature structure symmetrically relative to the magnetic devices 9c and 10c, with the same gap present between each of the pole elements 24 and the armature structure 26. The provision of equal gaps assists in maintaining equal impedances for the energizing windings 13a and 14a during normal conditions of operation of the circuit 1. A predetermined relationship between the impedances of the windings 13a and 14a is desirable in order to assure a predetermined division of the current component I_e therebetween.

Each of the magnetic devices when energized urges the armature structure 26 in the direction indicated by an associated arrow *c* or *d*. If the contacts 7 and 8 are to be disengaged under normal operating conditions of the circuit 1, the current components I_e and I_i should add in the energizing winding 13a and should subtract in the energizing winding 14a. This addition and subtraction is indicated by arrows in Fig. 7 which represent an instantaneous direction of flow for the current components I_e and I_i .

Since the operation of the relay 6e of Fig. 7 is similar otherwise to that of the relay 6 of Fig. 75

1, a more detailed description of the operation thereof appears unnecessary.

In view of the fact that the energizing windings 13a and 14a offer inductive reactance to the flow of current component I_e it may be desirable to increase the resistance value of the resistor 16 in order to keep the current component I_e substantially in phase with the voltage producing this current component. The armature structure 26 and the magnetic parts of the magnetic devices 9c and 10c may be constructed of a suitable magnetic material such as laminated soft iron.

In certain cases it may be desirable to insulate the path of the current component I_e from that of the current component I_i . Fig. 8 discloses a relay 6f wherein such insulation is provided. This relay corresponds closely to that of Fig. 7 but includes an auxiliary energizing winding 13b and 14b on each of the magnetic devices 9c and 10c. The current component I_i is supplied to the energizing windings 13a and 14a in the same manner as that disclosed for Fig. 7. In order to insulate the path for the current component I_i from that of the current component I_e , the current component I_e is supplied only to the auxiliary energizing windings 13b and 14b. To this end a path is established for the current component I_e from a conductor of the circuit 1 through a conductor 34, the auxiliary windings 13b and 14b, a conductor 35, and the resistor 16 to ground. From an inspection of Fig. 8 it will be noted that the auxiliary windings 13b and 14b are energized in opposite directions by the current component I_e . These directions are so selected that under normal operating conditions the magnetic fluxes produced by the current components I_e and I_i add in the magnetic device 9c and subtract in the magnetic device 10c. Consequently, the operation of the relay 6f is substantially similar to that of the relay 6e despite the fact that the paths for the current components I_e and I_i are electrically insulated from each other. Instead of the vector addition and subtraction of current components provided by the relay of Fig. 7, the relay 6f provides vector addition and subtraction of magnetic fluxes.

It will be noted that the construction shown in Fig. 8 eliminates the centrally disposed tap from the current transformer 15. A further modification wherein this tap is eliminated is disclosed in Fig. 9.

The system shown in Fig. 9 is substantially similar to that illustrated in Fig. 7 except for the provision of a winding extension 13c for the winding 13a. The path for the current component I_i remains substantially unchanged, this current flowing from the current transformer 15 through the energizing windings 13a and 14a in series. The path for the current component I_e is somewhat modified. This path may be traced from one conductor of the circuit 1 through a conductor 32, the energizing winding 14a, a conductor 33, the winding extension 13c, and the resistor 16 to ground. Under normal conditions of operation the magnetic fluxes produced by the current components I_i and I_e add in the magnetic device 9c and subtract in the magnetic device 10c. If the direction of energy flow in the circuit 1 reverses from the normal direction, the magnetic fluxes then add in the magnetic device 10c and subtract in the magnetic device 9c, thereby urging the movable contact 7 into engagement with the fixed contact 8. Therefore, the operation of the relay 6g disclosed in Fig. 9 is substantially

similar to that of the relays 6e and 6f of Figs. 7 and 8.

Although circuit connections for the contacts 7 and 8 of Figs. 7, 8, and 9 and cooperating controlled elements for the relays have been omitted for simplicity, it is to be understood that these contacts or cooperating controlled elements for the relays may be employed for any control operation such as that illustrated in Fig. 1 or 2.

In the translating or operating means herein referred to, it is desirable that the output or force developed by the means be proportional to the square of the resultant current employed for energization of the means. Both the thermoresponsive and magnetic types herein disclosed provide such a relationship of output to current.

Although the invention has been described with reference to certain specific embodiments thereof, numerous modifications thereof are possible. Therefore, the invention is to be restricted only by the appended claims.

I claim as my invention:

1. In an electrical protective system for an electrical circuit, means responsive to the relationship of a first quantity in said electrical circuit to a second quantity therein, comprising circuit control means, a pair of thermoresponsive operating means, means differentially responsive to said operating means for actuating said circuit control means, and selective energizing means dependent on the relationship of said quantities for selectively energizing either of said operating means in accordance with the sum of said quantities, said energizing means being effective for energizing the remaining operating means in accordance with the difference of said quantities.

2. In an electrical protective system for an electrical circuit, directional means controlled by the sum quantity and difference quantity of voltage and current present in said system, comprising circuit control means, a plurality of thermoresponsive operating means, means differentially relating said operating means for actuating said circuit control means, and energizing means selectively controlled by the direction of energy flow in said circuit for selectively energizing a first one of said operating means in accordance with either of said quantities, said energizing means including means for energizing a second one of said operating means selectively in accordance with the remaining one of said quantities.

3. In an alternating current system, a feeder circuit, a load circuit for receiving energy from said feeder circuit, and coupling means for coupling said load circuit to said feeder circuit, said coupling means including a circuit breaker for connecting and disconnecting said circuits, a winding, means for inducing in said winding a voltage controlled by the current flowing in said feeder circuit, a pair of translating means having an output proportional to the square of their energization, means connecting said translating means in series with said winding, first means for energizing said translating means in parallel in accordance with voltage present on the feeder circuit side of said circuit breaker, each of said translating means being energized in accordance with the vector resultant of currents supplied by said winding and said first means, and control means differentially responsive to the outputs of said translating means for tripping said circuit breaker.

4. In an electrical protective system for an electrical circuit, directional means controlled by the resultant sum quantity and difference quan-

5 tity of voltage and current present in said system, comprising circuit control means, a pair of thermally responsive operating means, means differentially relating said operating means for actuating said circuit control means, and energizing means selectively controlled by the direction of energy flow in said circuit for selectively heating a first one of said operating means in accordance with the square of either of said quantities, said energizing means including means for heating a second one of said operating means in accordance with the square of the remaining one of said quantities.

10 5. In an electrical protective system for an electrical circuit having a voltage quantity and a current quantity therein, an electrical path having a pair of arms, means for passing through said arms in series a current dependent on a first one of said quantities, means for passing through said arms in parallel, a current dependent on a second one of said quantities, and thermoresponsive means differentially responsive to the squares of the resultant currents traversing said arms for controlling an electrical circuit.

15 6. In an electrical protective system for an electrical circuit having a voltage quantity and a current quantity therein, an electrical path having a pair of arms, means for passing through said arms in series a current dependent on a first one of said quantities, means for passing through said arms in parallel a current dependent on a second one of said quantities, a first thermally responsive device connected for energization in accordance with the resultant current traversing a first one of said arms, a second thermally responsive device connected for energization in accordance with the resultant current traversing a second one of said arms, and means differentially responsive to the outputs of said devices for controlling an electrical circuit.

20 7. In a directional relay system for an electrical circuit having a voltage quantity and a current quantity therein, a transformer having its primary winding connected for energization in accordance with a first one of said quantities, an electrical path having two arms connected in series with the secondary winding of said transformer, means for energizing said arms in parallel in accordance with a second one of said quantities, translating means for developing an output controlled by the resultant current flowing through a first one of said arms, translating means for developing an output controlled by the resultant current flowing through a second one of said arms, and circuit control means differentially responsive to said outputs.

25 8. In a directional relay system for an electrical circuit having a voltage quantity and a current quantity therein, a transformer having a primary winding connected for energization in accordance with a first one of said quantities and having a secondary winding provided with a centrally disposed tap, a pair of thermally responsive motive devices, a pair of contacts disposed for actuation by said motive devices, a first one of said devices being effective when heated for moving said contacts together, and a second one of said devices being effective when heated for opposing said motion of said contacts, means connecting said thermally responsive devices with said secondary winding in a series circuit for energization therefrom, and means for energizing said thermally responsive devices in parallel in accordance with a second one of

said quantities, said last named means including a connection to said centrally disposed tap.

9. In an electrical protective system for an electrical circuit, directional means controlled by the sum quantity and difference quantity of voltage and current present in said system, comprising circuit control means, a plurality of operating means, means differentially relating said operating means for actuating said circuit con-

trol means, and energizing means selectively controlled by the direction of energy flow in said circuit for selectively energizing a first one of said operating means in accordance with either of said quantities, said energizing means including means for energizing a second one of said operating means in accordance with said sum quantity.

FLOYD D. JOHNSON.
